UNITED STATES PATENT OFFICE.

LEE W. V. WILMS, OF CHICAGO, ILLINOIS.

METATARSAL AND ANTERIOR FOOT-SUPPORT.

1,313,442.

Specification of Letters Patent. Patented Aug. 19, 1919.

Application filed January 31, 1919. Serial No. 274,157.

To all whom it may concern:

Be it known that I, LEE W. V. WILMS, a citizen of the United States, and a resident of Chicago, in the county of Cook and State 5 of Illinois, have invented certain new and useful Improvements in Metatarsal and Anterior Foot-Supports, of which the following is a specification.

This invention relates to foot supports of 10 a type in the form of a detachable or removable insole or device, to be comfortably worn within shoes or boots mainly of the ordinary commercial kind or construction, for the relief and correction of metatarsalgia 15 and "Morton's toe", as well as, for correcting, relieving and preventing various other anatomical defects, unnatural and objectional tendencies of the feet, and particularly those of the transverse and anterior arches 20 of said members, and it consists in certain peculiarities of the construction, novel arrangement and operation of the various parts thereof, as will be hereinafter more fully set forth and specifically claimed.

One of the objects of the invention is, to 25 provide a foot support of the above mentioned general character, which shall be simple and inexpensive in construction, strong, durable and efficient in operation, 30 and made in different sizes and widths, in order to be adaptable for use in shoes of various sizes, and in such manner that inserts or pads can be applied thereto or detached therefrom for the purpose of regulating 35 the height or elevation posterior of the metatarsal heads to support and correct the fallen or weakened condition of the transverse metatarsal arch of the foot. Another object is to furnish a foot support having 40 means at or near the front end of its inner longitudinal border for treating and relieving the pain of, as well as, correcting the malformation known as "bunions" or hallux 45 valgus, by giving support to the weakened transverse anterior arch, (which is most always prevalent where a weakened great toe 50 articulation (bunion) or a malformation of the first metatarsal phalangial articulation), hallux valgus, manifests itself, and by 55 crowding the misplaced metatarsal bone to its natural alinement, in parallel line with the other four metatarsal bones, taking tension and strain off the bunion articulation and thereby assisting nature to absorb the enlarged condition and relieving all pressure caused by the shoe at this abnormality.

A further object is to provide a support for the relief of distorted metatarsal phalangial articulation of the second, third and fourth toes, mainly the third and fourth, due 60 to the wearing and misfitting of shoes, generally too short, which have crowded the toes backwardly, thus causing the muscles of these toes to shorten, thereby drawing the toes up and back forcing the individual to 65 walk and pound on the heads of these metatarsals. The last above mentioned object is accompanied by balancing and giving support to the anterior metatarsal arch thereby 70 assisting nature to correct this painful maligancy.

Still another object of the invention is to provide support to the foot in all cases where the shank of the shoe is too short and has in its front portion a cavity or dish 75 shaped depression at the tread or ball which allows the foot to drop at the heads of the metatarsals, thereby bringing on painful conditions and deformities, and also to furnish means for giving additional support 80 and firmness at the plantar surface of the transverse and metatarsal arches where shoes are worn that are too weak or low in the shank between the heel and ball or tread.

In the accompanying drawing, which 85 serves to illustrate an embodiment of the invention—

Figure 1 is an plan view of one form of the device;

Fig. 2 is an outer edge view thereof; 90

Fig. 3 is a longitudinal sectional view taken on line 3, 3 of Fig. 1, looking in the direction indicated by the arrows;

Fig. 4 is a similar view showing the device supplied with an auxiliary or elevating 95 pad;

Fig. 5 is a cross sectional view taken on lines 5, 5 of Figs. 1 and 3 looking in the directions indicated by the arrows;

Fig. 6 is an enlarged fragmental plan 100 view of the front of the device showing a modification in its construction;

Fig. 7 is a detached perspective view of a pad used in the lateral pocket of said modified construction, and 105

Fig. 8 is a similar view to that shown in Fig. 6, but showing another modification in the arrangements of the foot supporting pads.

Corresponding reference numerals indicate like parts throughout the different views of the drawing, in which will be seen

and understood that the devices shown therein are all for the left foot, it not being deemed necessary to show the devices for the right foot, as they would be the same as those shown, except that the parts thereof would be located reversely.

In its simple form, the device consists of a composite insole or support of substantially the shape shown in Fig. 1 of the drawing, and of sufficient length to extend from the rear portion of the heel of the shoe in which it is to be worn to a point slightly in advance of the metatarsal heads of the foot and has its front portion tapered in a horizontal plane. This support is made up of an upper sheet 10 or piece of leather or other material, having a smooth or polished upper surface and possessing considerable rigidity and some resiliency, a lower piece 20 or sheet 11 of soft leather or other material of about the same size as the upper one, and an intermediate piece 12 of flexible material, which latter piece is somewhat narrower and shorter than the other pieces 25 so as to be enveloped thereby when the same are secured together by means of stitches 13 located at their side and rear edges only. The piece 12 is reinforced by a resilient strip 14 of metal which is secured by means 30 of rivets 15 at its ends to the piece 12 near its ends, as is clearly shown in Figs. 3 and 4 of the drawing, in which views it will be seen and understood that the metal piece 14 lies mainly under the piece 12, but has its 35 front portion extended through a transverse slot 16 in the piece 12 and secured to the upper surface thereof. Mounted on the upper surface of the front portion of the piece 12 is a pad 17 of any suitable material, 40 which is tapered toward all of its edges and is held in place between the front portions of the pieces 10 and 12 by means of the side stitches 13 and by securing said portions together in any suitable manner. 45 When thus arranged it will be understood that the front end of the lower piece 11 and the front portion of said piece will be free from the piece 12 as far back as the transverse stitches 18, which unite the lower 50 and intermediate pieces and that a pocket 19 or space will be provided for the reception of a pad 20 of any desired material and suitably fashioned used for regulating the elevation posterior of the metatarsal 55 heads to support and correct the fallen or weakened condition of the transverse metatarsal arch of the foot.

In Fig. 8 of the drawing is shown a slight modification in the construction of the support which consists of like parts arranged and combined in a similar manner to those shown in Figs. 1 to 5 inclusive, and above described, except that the permanent pad 17 is mounted on the lower surface of the 65 front portion of the intermediate piece 12

and is confined between said piece and the lower piece 11, instead of being located between the intermediate piece and the upper piece as before explained. In this modified form the front edges of the pieces 11 and 12 are secured together in any suitable way, but the front end of the upper piece is left free, to the end, that a pad 20 may be inserted into or removed from the pocket 21 or space between the front portions of the pieces 10 and 12, to be used for regulating the elevation posterior of the metatarsal heads as in the other construction and for a like purpose.

In Fig. 6 is shown another modified construction, which consists in providing the support, when constructed in either of the above described forms, with a pouch or pocket 22 of kid or soft material, which pouch is attached at one of its edges along the inner longitudinal border of the support and extends rearwardly from the front end thereof to a point rearwardly of the first metatarsal phalangial articulation, and is adapted to be turned upwardly so as to be located alongside of the foot. As shown, this pouch has its front end open and is tapered toward its rear end and is for the reception of a similarly tapered pad 23 of any desired cushioning material. The outer 95 surface of this pad is preferably rounded and its inner surface flat as shown.

This addition (consisting of the pouch and the pad) to the support, if for the purpose of treating and relieving the pain of, as well as, correcting the malformation known as "bunions" or hallux valgus, and its employment is as follows: The insert or pad is placed in the pouch with its flat surface disposed toward the foot so that when the shoe 105 is put on the pad will rest against and give support to the first metatarsal bone and will crowd the misplaced metatarsal bone to its natural alinement in parallel line with the other four metatarsal bones, thereby removing tension and strain from the bunion articulation and thus assisting nature to absorb the enlarged condition and minimizing the pressure caused by the shoe at this abnormality.

Having thus fully described my invention what I claim as new and desire to secure by Letters Patent is—

1. A device of the character described, comprising a laminated insole having an inner layer provided at its front portion with a tapered enlargement on one of its surfaces, and a resilient piece longitudinally mounted on said inner layer and secured thereto near each of the ends of said piece.

2. A device of the character described, comprising a laminated insole having an inner layer provided at its front portion with an enlargement on one of its surfaces, and a resilient piece longitudinally mounted

on said inner layer and secured thereto near each of the ends of said piece, said enlargement being enveloped by and confined between said inner layer and the outer layer 5 adjacent to said enlargement.

3. A device of the character described, consisting of an insole composed of three superimposed layers the outer ones of which being secured together at their side edges 10 and rear ends, the intermediate or inner layer provided at its front portion on one of its surfaces with an enlargement and secured at its front end to the outer layer adjacent to the enlargement, the front end of the 15 other outer layer being free.

4. A device of the character described, consisting of an insole composed of three superimposed layers the outer ones of which being secured together at their side edges 20 and rear ends, the intermediate or inner layer provided at its front portion on one of its surfaces with an enlargement and secured

at its front end to the outer layer adjacent to the enlargement, the front end of the other outer layer being free, and a pad removably 25 located in the space between the front portions of the last named outer layer and the inner layer.

5. A device of the character described, comprising a laminated insole having an 30 inner layer provided at its front portion on one of its surfaces with an enlargement and secured at its front end to the layer adjacent to said enlargement but free at said end from the layer adjacent to its surface opposite the enlargement, a pouch of flexible 35 material secured at one of its edges to the inner front margin of the insole, and a pad removably located in said pouch.

In witness whereof, I have hereunto subscribed my name this 29th day of Jany., 1919, at Chicago, Cook county, Illinois.

LEE W. V. WILMS.
